UNITED STATES PATENT OFFICE.

JESSE L. GIBSON, OF CENTERVILLE, INDIANA.

PELT STRETCHING AND DRYING DEVICE.

1,169,145.

Specification of Letters Patent. Patented Jan. 25, 1916.

Application filed February 13, 1915. Serial No. 7,933.

To all whom it may concern:

Be it known that I, JESSE L. GIBSON, a citizen of the United States, residing at Centerville, in the county of Wayne and State 5 of Indiana, have invented a new and useful Pelt Stretching and Drying Device, of which the following is a full and complete specification, the same being such as will instruct others to make and use the same with 10 exactitude.

In curing green pelts it is customary to first stretch the pelt over a tapering board or the like, but by that means it is impossible to attain the proper tension on the pelt 15 and it is also difficult to accomplish, and it also prevents the pelt from drying as rapidly as is desirable.

Therefore the principal object of my invention is to overcome the above mentioned 20 objections and at the same time produce a device which will be light in weight, strong and durable in construction, neat and attractive in appearance, easily operated and controlled, and which can be manufactured 25 and sold at a comparatively low price.

Another important object of my invention is to provide a device, of the character designated above, which is adjustable at both 30 of its ends, permitting the device to be used with various size pelts; and also having means for stretching the pelt longitudinally as well as laterally.

Other objects and particular advantages 35 of my invention will be brought out in the course of the following specification, and that which is new will be correlated in the appended claim.

The preferred means for carrying out my invention in a practical manner is shown 40 in the accompanying drawings, in which—

Figure 1 is a plan view of my entire device alone. Fig. 2 shows my device in operative position, with a pelt stretched thereupon. Fig. 3 shows an elevation of the 45 stretcher-bar alone. Fig. 4 shows an elevation of the spreader-bar, also showing the two frame arms therewith in cross section. Fig. 5 is a plan view of the upper end portions of the two arms, the connecting plate 50 being removed. Fig. 6 is an enlarged detail view of one of the movable hooks. Fig. 7 is an edge view of the upper portion of one of the main portions of the frame, showing the connecting plate. And Fig. 8 shows a 55 modified form for the main arms.

Similar indices denote like parts throughout the several views.

In order that the construction, the operation, and the advantages of my invention may be better understood and appreciated 60 I will now take up a detailed description thereof, in which I will set forth the invention as fully and as comprehensively as I may.

Referring now to the drawings in detail: 65 Numerals 1 and 2 denote the two main portions of the frame-arms, whose upper portions curve inward, forming the converging members 1^a and 2^a, respectively. The outer edges of the frame-arms are rounded or 70 beveled, as indicated at *a* and *b*, respectively, in order to dispense with sharp edges.

Formed in the end portions of the parts 1^a and 2^a are the respective threaded apertures 75 3 and 4, to receive screws.

Numeral 5 designates a triangular plate, with truncated corners, which is adapted to contact with the faces of the end portions of the members 1^a and 2^a, substantially as shown. Two lines of apertures, 6 and 7, are formed 80 through said plate, each line of apertures being parallel with one of the side edges of the plate 5. A pair of screws, 8 and 9, are adapted to be inserted in either one of said apertures 6 and 7, and then into their respective apertures 3 and 4, which manifestly 85 will pivot the upper ends of the arms, and then by changing the screws to other of the apertures 6 and 7 the upper end of the arms may be adjusted laterally apart.

Numeral 10 denotes the spreading-bar, which has the two open slots 11 and 12 therein, which open out at their ends. The said slots 11 and 12 are adapted to allow the arms 1 and 2 to operate therein, as shown in 95 Fig. 4. A plurality of apertures, 13 and 14, are formed through the outer portions of the bar 10, which are at right angles to the slots 11 and 12 and pass therethrough. Adapted to be inserted through the respective sets of apertures 13 and 14 are the removable pins 15 and 16, which are adapted 100 to hold the spreader-arm in place. Also formed along in the respective main portions of the frame arms, are the apertures 17 and 18 which extend therethrough, and are adapted to receive the pins 15 and 16, respectively.

Numeral 19 denotes the stretcher-bar, which has in each end portion the closed 110

end slots 20 and 21 in which may operate the main portions of the arms 1 and 2. Secured in the center of the bar 19, and extending upward at right angles to said bar, 5 is the stationary double hook 22. Located on each side of the hook 22 and pivoted in the bar 19 are the two movable double hooks 23 and 24. Each of the hooks 22, 23 and 24 is provided with both a long and a short 10 prong, and they are adapted to engage in the central portion of the tail-end of the pelt 25, which may be carried by the device, as shown in Fig. 2. The bar 19 is adapted to be drawn toward the bar 10, and then secured 15 by the pins 26 and 27, against which the upper edge of the bar engages, as in Figs. 1 and 2.

Modus operandi: From the above it will be seen that the upper end of the device 20 may first be adjusted to the width of the pelt, as is indicated at the upper ends of Figs. 1 and 2. The pelt 25 may then be drawn over the device as in Fig. 2. The lower ends of the arms 1 and 2 may then be 25 spread apart until the proper tension is obtained on the pelt, and the pins 15 and 16 may then be inserted in the proper apertures 13 and 14, and 17 and 18, respectively, which will hold the arms in lateral stretching 30 position. The bar 19 can then be moved up to the pelt and the hooks 22, 23 and 24 engaged therewith, after which the bar 19 should be drawn toward the bar 10 until the desired longitudinal tension is obtained 35 on the pelt, after which the pins 26 and 27 are inserted in the proper apertures 17 and 18 of the arms to hold the bar 19 in position, as in Fig. 2. By the above it will be seen that I am able to attain both lateral and 40 longitudinal tension to stretch the pelt, and to hold the pelt in stretched position indefinitely. Also by reason of the small contact of the device with the pelt, and holding the two parts of the pelt apart, I provide for 45 the air to circulate between the two parts of the pelt thereby hastening the drying process. If preferred, the arms 1 and 2, together with their upper portions 1^a and 2^a, may be made hollow, or curved, as shown 50 by the cross section of the arm A in Fig. 8, the curved portion or edge being outermost to engage the pelt.

I desire that it be understood that vari-

ous changes may be made in the several details of construction, from that herein 55 shown and described, without departing from the spirit of my invention and without sacrificing any of the advantages thereof, and also it is to be understood that the word "upward" and other similar terms are 60 merely used for convenience of description, and my device is not to be limited thereby.

Having now fully shown and described my invention, what I claim and desire to secure by Letters Patent of the United 65 States, is—

A pelt stretching and drying device, comprising in combination, a pair of arms having rounded outer edges and whose upper ends curve inwardly toward each other and 70 having threaded apertures formed through said end portions, a triangular plate adapted to contact with the faces of said end portions of the arms, there being two lines of apertures formed through said 75 plate, screws adapted to be inserted in said apertures in the plate and secured in said threaded apertures of the curved portions of the arms whereby the curved portions of the arms are made adjustable with 80 relation to each other, a spreader-bar having two open slots therein opening out at the ends and adapted to allow said arms to operate therein, there being a plurality of apertures formed through the outer portions 85 of said bars, removable pins adapted to be inserted in said apertures in the spreader-bar to hold the spreader-bar in place, there also being a plurality of apertures formed in the arms to receive said pins, a stretcher-bar 90 having slots in its ends in which may operate the main portions of the arms, a stationary double hook secured in the center of the stretcher-bar, movable hooks pivoted in the stretcher bar and located on each side of the 95 double hook, and pins adapted to be inserted in apertures in the arms to hold the stretcher-bar in adjusted position, all substantially as shown and described.

In testimony whereof I have hereunto 100 subscribed my name to this specification in the presence of two subscribing witnesses.

JESSE L. GIBSON.
